ELECTRIC LAMP FIXTURE

Filed Jan. 14, 1930

UNITED STATES PATENT OFFICE

CHARLES INNESS BROWN, OF QUEENS VILLAGE, NEW YORK

ELECTRIC LAMP FIXTURE

Application filed January 14, 1930. Serial No. 420,698.

This invention relates to lamp fixtures adapted more particularly for use in conjunction with electric incandescent lamps. More specifically, the invention contemplates the provision of a lamp fixture for supporting a lamp and shade or reflector therefor in simple and attractive fashion, and in such manner that the shade may be removed or replaced with facility. To this end a lighting fixture is provided wherein the shade or reflector is supported between the walls of a channel shaped holder.

The invention is especially applicable to electric desk lamps which utilize a shade or reflector of inverted trough shaped configuration supported at the rear for directing the light rays downwardly upon the desk free from shadows. The invention will be described particularly with reference to a lamp of this type, although it will be obvious that the novel features thereof may be applied to other types of lamps as well.

In desk lamps of the type specified heretofore in use, the means for supporting the reflector in each instance contains certain objectionable features. With some constructions at present utilized, the rear wall of the shade has affixed thereto, protective metallic plates covering or surrounding a border opening therein for supporting the shade upon a bracket affixed to the standard, which bracket also is adapted to support the lamp within the shade. In other constructions the lamp is provided at its edge with a hooded lateral projection adapted to be housed within a channel shaped support mounted upon a standard. Special clamping means are in this instance provided for retaining the shade in position.

The first of the arrangements mentioned is open to the objection that a special tool or wrench and some degree of mechanical skill are required for removing or replacing the shade. In the last instance mentioned the clamping means provided is cumbersome and somewhat difficult to manipulate, and with all of the arrangements the supporting structure for the shade appears to be relatively expensive as compared to the function performed.

The present invention overcomes the above objections in that the construction is of the most economical sort, the holder for the shade consisting merely of a single sheet of resilient material having the desired configuration. Likewise in the preferred embodiment as regards the shade, a very slight offset or transverse displacement of the wall adjacent the edge is all that is required for clamping purposes.

Inasmuch as with the present invention the holder retains the shade in position by means of a resilient action, the removal or replacement of the shade is accomplished quite easily, requiring as it does only the exertion of a slight force to overcome the spring-like action of the clamp.

One of the features of the invention consists in the formation of a suitable conduit in the sides and base of the holder for conveying the electric wires from the supporting structure or standard affixed to one side of the holder to an electric light socket affixed to the other side thereof without interference with the lamp shade when in position, while at the same time providing a structure of neat and harmonious appearance.

In accordance with the invention, the shade is supported at its edge midway lengthwise of its rear side. To this end the shade at this point is provided with a substantially rectangular offset or transversely displaced portion extending from the edge and terminating in a sloping shoulder furthest therefrom. The offset is such as to provide a recess to the outer surface and a corresponding embossment upon the inner surface of the shade.

The holder which as stated is made of a sheet of resilient material, preferably metal, is formed into a narrow channel section having its sides spaced apart corresponding to the thickness of the shade. The sides of the holder are further provided with an offset intermediate the aligned ends thereof such that the inner walls of the sides will conform to the contour of the shade in the region including the offset portion and extending a short distance on both sides thereof.

As a result of this arrangement the shade

is adapted to be supported at its edge by having a portion of its side including the offset housed between the resiliently engaging sides of the holder. Since the offset of 5 the shade when properly supported is situated within the corresponding offset of the holder, longitudinal movements or shiftings of the shade are thus prevented.

The sides of the holder within the offset 10 are preferably higher than at the ends, the heights being so chosen that with the shade supported in the holder, the side portion thereof engaging the recess in the outer surface ends just below the sloping shoulder 15 which connects the offset in the shade to the side proper. On the other hand, the side portion of the holder engaging the embossment upon the inner surface extends over and curves in conformity with the shoulder. 20 As a result of this arrangement the shade is not only resiliently clamped against movement in a vertical direction, but is also properly braced against the bending stress set up due to the fact that the center of gravity of 25 the shade is not vertically in line with its support.

An electric light socket is affixed to the side portion of the holder which engages the inner embossed surface of the shade so that 30 the light source will be properly shaded thereby. A support or standard is affixed to the opposite side of the holder for supporting the fixture. In order to provide a conduit for the electric wires extending from the 35 standard to the light socket, a channeled recess is formed upon the inner walls and bottom of the holder, extending transversely thereof between the points of affixment of the standard and the light socket, where suitable 40 apertures are formed in the sides for leading the wires away from the holder. The recess formed upon the inner surfaces of the holder appears as a corresponding embossment or 45 piped projection upon the outer surfaces thereof.

The wires when thus situated within the recess, lie below the inner clamping surfaces and hence do not interfere with the housing 50 of the shade within the holder. Furthermore, the piped projection upon the outer surfaces of the holder gives a pleasing and balanced appearance thereto.

Having thus described the invention in 55 general terms, a detailed explanation will now be given with reference to the drawings of which:

Fig. 1 shows a front elevation of the lamp fixture partly in section taken along the line 60 1—1 of Fig. 2.

Fig. 2 shows a sectional view taken along the line 2—2 of Fig. 1.

Fig. 3 shows a sectional view taken along the line 3—3 of Fig. 1.

Fig. 4 shows a fragmentary sectional view

disclosing the holder construction and taken along the line 4—4 of Fig. 1.

Fig. 5 is a sectional view of the holder taken along the line 5—5 of Fig. 1.

Fig. 6 is a plan view of the lamp fixture 70 with the shade removed and adapted to disclose the construction of the holder.

Fig. 7 is a perspective of the lamp shade which shows the formation of the offset portion adapted to engage the holder. 75

Like elements are similarly designated in the several figures.

Referring to the drawing, the upper portion of a standard or other supporting structure 1 terminates in one-half 2 of a spherical lock 80 nut 3 having serrated teeth engaging the opposite half 4 clamped thereto by means of a screw S, the portion 4 forming part of a bracket affixed to one side 5 of a channel shaped holder 6. The holder 6 supports at its edge a shade or reflector 7 of inverted trough shaped configuration adapted to shade the electric light sources 8 and 9 screwed into the opposite sides of a double socket 10.

The shade 7 has located midway lengthwise of its rear vertical side and extending inwardly a certain distance from the edge thereof, a substantially rectangular portion 12 offset or transversely displaced inwardly, 95 constituting a recess in the outer surface and an embossment upon the inner surface of the shade. The displaced portion 12 is joined on three sides to the main body of the shade by the sloping shoulders 13, 14 and 15.

The holder 6 made of a single sheet of resilient material and formed into a narrow channel section, is provided with an offset 16 intermediate the aligned ends 17 and 18 such that the sides of the holder conform to the contour of the shade in the region including the offset and extending a certain distance on both sides thereof as shown in Fig. 5.

When viewed in side elevation as shown in 110 Fig. 1 the holder has the shape of a Greek cross with the lower extension cut away, the sides being higher within the offset than at the ends. The height of the side portion engaging the recess in the outer surface of 115 the shade is such that with the shade clamped in position, the upper edge 19 of this side is situated just below the shoulder 15 of the shade. On the other hand the portion of side 11 of the holder which engages the embossed inner surface of the shade is of such height as to extend over the shoulder 15 being curved at its free edge 20 in conformity with the contour of the shade as is clearly shown in Figs. 2 and 3.

In order to provide a conduit for the necessary electric wires to extend from the standard 1 to the light socket 10, a piped projection 23 is formed in the sides and base of the holder intermediate the ends and extending 130

transversely thereof between bosses 24 and 25 formed upon sides 11 and 5 respectively.

The bosses and the piped projection provide corresponding recesses upon the inner surfaces of the holder within which is situated the lamp cord 26. The bosses 24 and 25 contain perforations 21 and 22 respectively as shown in Fig. 2 for affixing the light socket 10 and the lock nut bracket 4 respectively to the clamp and also to provide openings in the recess for leading the wires 26 away from the holder. To this end the lock nut 3 and support 1 are of hollow construction, as is clearly indicated in Fig. 2.

Figs. 2 and 5 delineate the manner in which the lamp cord 26 and shade 7 are housed within the holder without interference to one another; while Figs. 1, 3 and 6 show the neat and harmonious appearance of the electric cord conduit as viewed externally.

A modified form of the invention consists in providing the shade with a recess or slot extending inwardly from the edge and adapted to engage a corresponding projection formed in the base of the channel shaped holder, for preventing longitudinal movement of the shade in the holder. With this modification it is not required that the shade and holder be offset, nor is it necessary that the sides of the clamp resiliently engage the shade.

I claim:

1. In a lamp fixture, a standard having one side of a channel shaped holder affixed thereto, a light source affixed to the opposite side of said holder, a reflector for said light source supported at its edge within said holder, said reflector being provided at its point of support with a recess adapted to engage a corresponding projection formed in said channel, said holder being provided with a conduit adjacent the base of said channel for extending electric wires from said standard to said light source without interference to said reflector.

2. In an electric lamp fixture, a reflector having a substantially rectangular recess at its edge, a channel shaped holder for said reflector having sides adapted to resiliently engage said reflector and a projection engaging said recess for preventing movement of said reflector in said holder, a standard pivotally affixed to one side of said holder, and a light source affixed to the opposite side thereof in operative relation to said reflector.

3. In an electric lamp fixture, a reflector having a recess at its edge, a channel shaped holder for said reflector having sides adapted to engage said reflector and conforming to the contour thereof in the region including said recess for preventing movement of said reflector in said holder, a standard pivotally affixed to one side of said holder, and a light source affixed to the opposite side thereof in operative relation to said reflector, and a con-

duit formed in said holder for extending electric wires from said standard to said light source.

4. In combination, a lamp shade having extending inwardly and terminating in a sloping shoulder a certain distance from an edge thereof, a transversely displaced portion constituting a recess in one surface and a corresponding embossment upon the opposite surface thereof, whereby said shade may be removably supported between the resiliently engaging sides of a channel shaped holder associated therewith, the sides of said holder conforming to the contour of said shade in the region including said displaced portion and extending on both sides thereof, said holder having the side portion engaging said embossment extending over said shoulder and curving in conformity therewith for resiliently clamping said shade against movement in any direction, a light source affixed to one side of said holder and extending beneath said shade, and a supporting structure affixed to the other side of said holder.

5. In combination, an incandescent lamp shade of inverted trough shaped configuration having extending inwardly and terminating in a sloping shoulder a certain distance from the edge on one side thereof, a transversely displaced portion constituting a recess in the outer surface and a corresponding embossment upon the inner surface thereof whereby said shade may be removably supported between the resiliently engaging sides of a channel shaped holder associated therewith, said holder having sides conforming to the contour of said shade in the region including said displaced portion and extending on both sides thereof, with the side portion engaging said embossment extending over said shoulder and curving in conformity therewith, a piped projection terminating in bosses formed in the sides and base of said holder and extending transversely thereof from an intermediate point in one side to an intermediate point in the opposite side, means including apertures in said bosses for affixing a supporting structure to the side of said holder adjacent said recess in and a lamp socket to the side thereof adjacent said embossment upon said lamp shade respectively, said piped projection and bosses forming corresponding recesses upon the inner surfaces of said clamp to form a conduit for electric wires extending from said lamp socket to said supporting structure without interference to said shade when clamped in position.

6. In combination in an electric lamp fixture, a reflector having extending inwardly from an edge thereof a certain distance, a recess formed in the outer surface and a corresponding embossment upon the inner surface thereof, whereby said reflector may be removably supported between the resiliently engag-

ing sides of the channel shaped holder associated therewith, the sides of said holder conforming to the contour of said shade in the region including said recess and embossment 5 respectively, for resiliently supporting said reflector against movement in any direction, an embossment formed upon the sides and base of said holder extending from an intermediate point of one side transversely there- 10 of to an intermediate point on the other side, said embossment providing a corresponding recess upon the inner surfaces of said clamp for reception of a lamp cord without interference to said shade, said cord passing 15 through a perforation in one termination of said embossment to a supporting structure affixed thereto, and extending through a second perforation in the opposite termination of said embossment to a lamp socket affixed 20 thereto and operatively positioned relative to said reflector.

7. In combination in an electric lamp fixture, a reflector having extending inwardly from the edge thereof a certain distance, a 25 transversely displaced portion forming a recess in the outer surface and a corresponding embossment upon the inner surface thereof whereby said reflector may be removably supported between the resiliently engaging sides 30 of a channel shaped holder associated therewith, said holder being made of a single sheet of metal having sides conforming to the contour of said shade in the region including said displaced portion for resiliently clamping 35 said shade against movement in any direction, a recess formed upon the inner sides and base of said holder and extending transversely of said channel from an intermediate point on one side to an intermediate point on 40 the other, said recess providing a conduit for reception of electric wires without interference of said shade, said wire extending through perforations in the opposite terminations of said recess to a supporting structure 45 and a lamp socket affixed respectively to the opposite sides of said holder.

8. A lamp shade having extending inwardly a certain distance from an edge thereof, a 50 transversely displaced portion constituting a recess in one surface and a corresponding embossment upon the opposite surface of said shade, whereby said shade may be removably supported between the resiliently engaging sides of a channel shaped holder conforming 55 to the contour of said shade in the region including said displaced portion and extending on both sides thereof, such a holder having the side portion engaging said embossment extending beyond the remainder of said side 60 and curving in conformity with the inner termination of said embossment, for resiliently clamping said shade against movement in any direction.

9. An incandescent lamp shade of inverted 65 trough shaped configuration having a sub-

stantially rectangular transversely displaced portion extending inwardly and terminating in a sloping shoulder a certain distance from the edge in one side thereof, constituting a recess in the outer surface and a corresponding embossment upon the inner surface of said shade, whereby the same may be removably supported between the resiliently engaging sides of a channel shaped holder conforming 70 to the contour of said shade in the region including said displaced portion and extending a certain distance on both sides thereof, with the portion of said side engaging said embossment extending over and curving in conformity with said shoulder for preventing movement of said shade in any direction when supported in said holder, and with the portion of the side engaging said recess ceasing below 75 said shoulder.

10. A holder for supporting at its edge a lamp shade, said holder being of narrow channel shape with resilient sides containing an offset portion intermediate the aligned ends thereof, one side extending within said offset beyond and being bent over at its end toward the other leaving sufficient space between the opposed edges for inserting said shade, the surface portions of which adapted to engage said holder are shaped in conformity with the inner walls thereof for resiliently clamping said shade against movement in 80 any direction.

11. A holder for supporting at its edge a lamp shade, said holder being of narrow channel shape with resilient sides containing an offset portion between the aligned ends thereof, one side extending within said offset beyond and being bent over at its end toward the other leaving sufficient space between the opposed edges for inserting said shade, the surface portions of which adapted to engage said holder are shaped in conformity with the inner walls thereof for resiliently clamping said shade against movement in 85 any direction, means provided upon one side of said holder for affixing a light socket and upon the other side for affixing a support thereto, and a conduit adapted to receive a lamp cord extending between said means transversely of said channel following the 90 side and bottom contour thereof.

12. A holder for supporting at its edge a lamp shade of rigid structure, said holder being made of a sheet of resilient material formed into a narrow channel section with 95 sides containing an offset portion intermediate the aligned ends thereof, one side extending within said offset beyond and being bent at its end toward the other leaving sufficient space between the opposed edges for inserting said shade, the surface portions of which adapted to engage said holder are shaped in conformity with the inner walls thereof for resiliently clamping said shade 100 against movement in any direction, means in- 105

cluding an aperture in one side of said holder for affixing a light socket thereto, means including an aperture in the opposite side of said holder for affixing a support thereto, and
5 a piped projection formed upon the sides and bottom of said clamp extending between said apertures providing upon the inner surfaces of said channel a recess adapted to receive a lamp cord extending from said support to
10 said socket without interference to the clamping of said shade.

13. In a lamp fixture, a reflector containing a substantially planar section adjacent an edge, a recess formed in one surface of said section and a corresponding embossment upon its opposite surface, a channel-shaped holder for said reflector having flexible sides conforming to the contour of said recess and embossment for supporting said reflector
15 against movement through resilient engagement therewith, means supporting said holder and a light source associated therewith shaded by said reflector.

14. In a lamp fixture, a channel-shaped holder having flexible sides containing a transversely displaced portion intermediate the ends thereof, a reflector supported by said holder, said reflector containing an offset portion adjacent an edge corresponding in dimension to the transversely displaced portion of said holder, whereby said reflector is maintained against movement within said holder by the snap-action thereof, means supporting said holder, and a light source shaded by said reflector.

15. In a lamp fixture, a channel-shaped holder having flexible sides containing a transversely displaced portion intermediate the ends thereof within which one side extends above and curls slightly toward the other, a reflector supported by said holder, said reflector containing an offset portion adjacent an edge corresponding to the transversely displaced portion of said holder,
40 whereby said reflector is insertible in said holder by snap-action thereof, means supporting said holder, and a light source shaded by said reflector.

50 In testimony whereof I affix my signature.
CHARLES INNESS BROWN.
